UNITED STATES PATENT OFFICE.

VENCIL MARUSKA, JR., OF RED CLOUD, NEBRASKA.

WALL-PAPER HANGER.

1,286,047.

Specification of Letters Patent. Patented Nov. 26, 1918.

Application filed December 30, 1916. Serial No. 139,726.

To all whom it may concern:

Be it known that I, VENCIL MARUSKA, Jr., a citizen of the United States, residing at Red Cloud, in the county of Webster and 5 State of Nebraska, have invented certain new and useful Improvements in Wall-Paper Hangers; and I do hereby declare the following to be a full, clear, and exact description of the invention, such as will enable 10 others skilled in the art to which it appertains to make and use the same.

This invention relates to improvements in wall paper hanging devices, and has for its primary object the provision of a device 15 of this nature that will admit of the paper being hung in a more convenient and expeditious manner, and which includes a paste distributing tank for applying paste to the paper previous to the paper being presented 20 to the wall.

Another object of the invention is the provision of a device of this character which will be of simple and durable construction, cheap to manufacture and efficient in operation.

Other objects will appear and be better understood from that embodiment of my invention of which the following is a specification, reference being had to the accompanying drawing forming a part thereof, in which:

Figure 1 is a front elevation of the paper hanging device,

Fig. 2 is a side view thereof,

Fig. 3 is a vertical sectional view taken through the paper hanging device, and

Fig. 4 is a side view of the paste distributing tank, showing the outlet therein.

Referring to the drawing in detail, the 40 paper hanging device is shown as consisting of a substantially U-shaped frame 1, which has the connecting portion for the sides thereof substantially V-shaped, as shown in Fig. 1, and formed integral with the apex portion 45 of the V-shaped connecting portion for the sides of the frame is a sleeve 2, that receives one end of the handle 3. The sides of the V-shaped connecting portion for the sides of the frame are braced by means of a bar 4, 50 which has its opposite ends connected to the respective sides of the V-shaped portion, as shown in Fig. 1 of the drawing. The respective side portions of the frame 1 are provided with inclined slots 4, the slot in 55 each side opening into one of the side edges of the sides of the frame, as shown in Fig. 2,

and the said slots rotatably receive the opposite ends of a shaft 5, the shaft 5 having a roller 6 thereon around which is wound the wall paper designated 7. A second 60 roller, designated 8, is interposed between the sides of the frame 1, adjacent the free ends of the sides, and is carried by a shaft 9, the opposite ends of which are journaled in openings in the sides of the frame, the 65 roller 8 being adapted to have the wall paper pass thereover, and is adapted to serve as a presser roller for pressing the pasted paper into engagement with the wall so as to securely fasten the paper on the wall. A 70 pair of laterally extending and V-shaped brackets 10 are formed integral with the sides of the frame 1, as shown in Fig. 2, and are provided with slots 11, which removably receive lugs 12 carried by the opposite ends 75 of an elongated cylindrical shaped tank 13. Suitable fastening elements 14 are pivotally associated with the V-shaped bracket 10 and have notches therein for engaging over the lugs 12 so as to prevent accidental withdrawal of the lugs from the slots during the 80 paper hanging operation. The tank 13 is adapted to contain paste and is provided on one side with an elongated discharge opening or slot 15, through which the paste is 85 discharged. The tank is also provided with a suitable filling spout 16, at one side thereof, and which is normally closed by means of a removable cap 17.

In use, a roll of paper is wound around 90 the roller 6, and one end of the paper is then drawn over the tank 13 and passed over the discharge slot 15, so as to admit of a coating of paste being applied to the paper, the terminal of the end of the paper being then 95 passed over the presser roller 8. The paper hanging device is then canted and the end of the paper presented to the wall and pressed into engagement therewith by means of the presser roller 8. The frame 1 is then 100 moved downwardly along the wall, so as to effect unrolling of the paper and the application of the same to the wall.

Various changes might be resorted to in the construction, form and arrangement of 105 the several parts without departing from the spirit and scope of the invention as claimed.

Having thus described my invention what I claim as new, is:

A paper holding device consisting of a substantially U-shaped frame, a paper hold-

ing and a pressure roller carried by said U-shaped frame, V-shaped brackets carried by the U-shaped frame, a paste-holding receptacle detachably supported by the V-shaped brackets, said paste-holding receptacle being supported in a position between the paper holding roller and the presser roller, and adapted to keep sufficient tension on the paper to prevent the same from unwinding too

freely when the paper is being applied to 10 the wall.

In testimony whereof I affix my signature in presence of two witnesses.

VENCIL MARUSKA, Jr.
